PUMP

Louis W. Lewis, Dallas, Tex.

Application April 26, 1948, Serial No. 23,205

9 Claims. (Cl. 230—74)

1

This invention is concerned with a pump, and particularly with a pump which is adapted to deliver either small or large quantities of fluid without appreciably changing the pressure, volume or temperature of the fluid being delivered.

Most pumps heretofore used, such as reciprocating pumps, centrifugal pumps, rotary pumps, gear pumps and air pressure pumps, do change the pressure, the volume or the temperature of the fluid being delivered by the pump.

In order to deliver a constant flow of fluid, reciprocating pumps heretofore used must build up a head, or store a quantity of liquid or fluid under pressure, so that when the fluid is delivered, as through a small aperture, the fluid will flow continuously. Most such pumps have a reserve chamber, sometimes cushioned with air so that more liquid will be admitted into the reserve chamber by compressing the resilient air or other fluid in it, thus getting a continuous flow of fluid.

Gear pumps, reciprocating pumps, rotary pumps, centrifugal pumps and air or gas pressure pumps heretofore used have delivered a constant flow of fluid because of the pressure exerted against it.

Most pumps used in the past have been unable to deliver very small quantities of fluid in exact and fixedly measured quantities or increments, because most of these pumps depend for their efficiency upon the speed of operation and the pressure used for forcing the fluid to the delivery point. Therefore, the fluid delivered by these pumps is necessarily changed in volume, pressure and temperature. This is especially true in the pumping of gases.

The present invention is intended to provide a pump especially useful in laboratories and other places where it is necessary to deliver precisely metered and exactly measured quantities of fluid, either gases or liquids, either in continuous flow or in intermittent quantities, without appreciable change in the pressure, volume and temperature of the fluid delivered.

In addition to the objects above set out, this invention has among its objects the following:

(a) To provide a method and apparatus for moving fluids in successively moved quantities, and in which each quantity so moved will remain constant in volume, pressure and temperature.

(b) To provide a pump with a fluid piston operated by gravity.

(c) To provide a pump with fluid operated valves, which valves are operated by gravity.

(d) To provide method and apparatus for pumping fluids which will pump various, meas-

2

ured quantities of fluid without appreciable change in pressure, volume or temperature of the fluid while being pumped.

(e) To provide method and apparatus for moving fluid in which there is delivered a continuous flow of fluid, or a series of spaced quantities of fluid, without appreciable change of volume, pressure or temperature of the fluid moved.

(f) To provide a pump which may be adapted for the circulation of a fluid in measured quantities without appreciable change in the volume or temperature of the circulated fluid.

(g) To provide a pump which may operate as a vacuum pump for exerting a steady and gentle suction.

(h) To provide a pump which will deliver a plurality of fluids simultaneously without appreciable change in pressure, volume or temperature of such fluids.

(i) To provide a pump which will exert a steady and gentle pressure.

(j) To provide mechanism whereby fluids may be moved in increments without pressure, through a closed conduit system so operated as to prevent contact of the moving fluid with the atmosphere and/or contamination therefrom.

(k) To provide an oscillating valve which is opened and closed by the gravitation therein of a body of liquid.

(l) To provide method and apparatus for moving successively entrapped quantities of fluid within a fully enclosed pumping system operated at the environmental pressure, and in which the force of gravity is employed to valve and to move the successively entrapped quantities of fluid.

(m) To provide fluid measuring and moving method and apparatus employing liquid-actuated valves, and means for tilting, cocking, inclining or leaning such valves so as to cause the liquid therein to be moved by gravity to open and close the valves, and in which there is further employed a liquid piston for drawing fluid into a receptacle associated with each of such valves, and also for displacing such fluid in such receptacles, depending upon the relative elevations of a pair of such valves, each of which is responsive to one common liquid piston.

In the drawings:

Fig. I is a perspective view of a preferred form of my invention.

Fig. II is an enlarged, partially sectionalized, side elevational view of a typical cylinder and valve assembly shown in Fig. I, with the mountings therefor.

Fig. III is an enlarged, front elevational view

of the cylinder and valve assembly shown in Fig. I with the mountings therefor.

Fig. IV is a perspective view of a modified form of cylinder and valve assembly which may be used with my pump.

Fig. V is a schematic representation showing various positions in which valve assemblies, shown in Fig. I, may be found during one complete cycle of the pump.

Fig. VI is a perspective view of the five way collector tube used in my device, showing the connector tubes and discharge hose connected thereto.

Fig. VII is a partially sectionalized elevation of a liquid container with siphon tube therein which may be used in conjunction with my pump for pumping liquids.

Fig. VIII is a perspective view of a pair of modified valve and cylinder assemblies employed to adapt the pump for delivering a multiple flow of fluids simultaneously.

Fig. IX is a schematic representation showing the various positions of two cooperating valve assemblies on my pump, during one complete cycle of operation.

In the drawings numeral references are used to designate various parts of my invention; and the numeral 1 designates the base of the framework of the pump. The four upright frame members 2, 3, 4 and 5, together with the cross braces 27 and 27a, complete the supporting frame-work of the pump.

An electric motor 66 has a gear 67, attached to the rotor thereof, which articulates with gear 6, which in turn drives the gears 7, 8 and 9 in the directions shown by arrows on the respective gears. It is to be noted that the gears 6, 7, 8 and 9 are all of the same diameter and are in the same ratio so that they all turn at the same rate of speed. The gears 6 and 8 are journaled to and supported by the cross braces 27 and 27a by means of rods 6a and 8a respectively, which rods are rotatively carried by the cross braces 27 and 27a through the use of bearings, such as 6b, 6c and 8b.

The gears 7 and 9 are mounted on the axles 10 and 11, respectively, which axles pass through, and are carried by, bearings 12 and 13. The opposite ends of the axles 10 and 11 pass through the upright members 3 and 2, respectively, to be secured to the crank arms 14 and 17, respectively, by means of bolts 14a and 17a, respectively. The crank arms 15 and 16 may be attached to the ends of the axles 10 and 11 respectively, in the same manner that crank arms 14 and 17 are attached thereto. The shafts 28, 29, 30 and 31 are secured to the outer ends of the crank arms 14, 15, 16 and 17, respectively, by means of bearing members 22, 23, 24 and 25, which bearing members are respectively held in place by pivot bolts 18, 19, 20 and 21.

The shafts 28, 29, 30 and 31 are supported by, and slide through, oil-lite bushings, such as those shown at 32 and 33. These bushings are rigidly connected to the ends of axles 34 and 35, which axles pass through and are supported by the bearings 36, 37, 38 and 39, so that the axles are rotatively connected between the upright frame members 2, 3, 4 and 5.

The opposite ends of the axles 34 and 35 are free to rotate independently, and even in opposite directions, since each of these axles is made of two separate members held together by differential sleeve couplings 40 and 41.

The glass or plastic cylinders 42, 43, 44 and

45 are fixed to the upper ends of the shafts 28, 29, 30 and 31, respectively, between lower brackets 46, 47, 48 and 49, and upper brackets 46a, 47a, 48a and 49a, respectively. These brackets are held firmly in place to the shafts by means of set screw collars 50 and 51 and set screws 50a and 51a, as is clearly illustrated in Figs. II and III.

Mounted on the upper ends of cylinders 42, 43, 44 and 45, and made integral therewith (if desired), are valve assemblies 52, 53, 54 and 55, respectively. These valve assemblies communicate with the respective cylinders to which they are connected. As shown in Fig. I all of the valve assemblies and their associated cylinders are exactly alike, and the shape and the construction thereof may be understood more fully by referring to Figs. II and III, where typical arrangements are disclosed. Of course, various are the forms of the cylinders and valve assemblies which may be used in this pump.

The valve assembly 52 has upstanding hollow branches 56 and 56a; the valve assembly 53 has upstanding hollow branches 57 and 57a; the valve assembly 54 has upstanding hollow branches 58 and 58a; and the valve assembly 55 has upstanding hollow branches 59 and 59a.

The branches on the respective valve assemblies may be made integral with, and communicate with their associated cylinders, through hollow connecting stems, as illustrated by the numerals 60 and 61.

Each of the valve assemblies 52, 53, 54 and 55 is provided with a quantity of mercury 62, 63, 64 and 65, placed in the lower horizontal part thereof. This mercury is in sufficient quantity to block the passage in the lower arm of the valve assembly when the valve assembly is tilted from the horizontal, as shown in Fig. I, but not sufficient in amount to prevent the free communication between the upper branch of the valve and the piston through the connecting stem.

The lower end of each of the cylinders 42, 43, 44 and 45 is extended, as clearly illustrated in Figs. II and III, to form a tubular projection, designated as 42a, on the bottom thereof.

A rubber, or other flexible tube 68, is attached at its opposite ends to the extension on the bottom of cylinders 42 and 45, so that these cylinders communicate with each other through the tube 68.

Likewise, the cylinders 43 and 44 are connected by the flexible hose 69 in the same manner that cylinders 42 and 45 are connected.

The tube 68 has a quantity of mercury 70 therein, which, as shown in Fig. I, extends up into cylinder 42, since the cylinder 45 is there shown at a higher level than cylinder 42. The level of the mercury is indicated by the dotted line to B.

Since by force of gravity the ends of the column of mercury in tube 68 will always seek the same level, the mercury will rise into the cylinder 42 or 45 when one is lower than the other. Cylinder 42 is shown in a lowered position in Fig. I; and the mercury has risen into it.

Likewise, flexible tube 69 has a quantity of mercury 71 therein, the level of which is indicated by the dotted line to A. In Fig. I the mercury is shown as having risen in the cylinder 43, it being lower than cylinder 44.

The volumes of mercury 70 and 71 act as fluid pistons for the pump.

A five-way collecting tube 72 is connected to,

and communicates with the branches 56a, 57a, 58 and 59a of valves 52, 53, 54 and 55, respectively, by means of flexible hoses 74, 75, 76 and 77, respectively. This is also shown in Fig. VI.

The discharge hose 73 is connected to the outlet branch 73a, for the purpose of discharging fluid from the pump.

Fig. IV shows a modified form of valve assembly designated as 78, which has, instead of a cylinder like that of 42, a cylinder 79, which is adapted for the delivery of very small quantities of fluid. In this form the upper part of the valve assembly is constructed the same way as the valve assemblies 52, 53, 54 and 55. It has upstanding hollow branches 80 and 81, and the branches 80 and 81 may be made integral with, and they communicate with, the cylinder 79 through extension tube 82.

The cylinder 79 is attached to the rod 84 by means of the clamp member 83. The flexible tube 85 (which is the same in construction and operation as tubes 68 and 69, shown in Fig. I) is attached to the cylinder 79 and leads off to another cylinder (not shown) which cooperates with the valve assembly 78 in the same general manner that valve assemblies 52 and 55 cooperate.

However, the openings through the branches 80 and 81, connecting extension 82 and cylinder 79 are the same size; and there is, therefore, no change in the pressure, volume or temperature of the fluid passing through it. The modified construction shown in Fig. IV assumes great importance in work of exact, precise and scientific nature.

Fig. VIII shows another modified form, wherein two valve assemblies are mounted together on the same rod, each such valve assembly being capable of delivering a different quantity and/or kind of fluid at the same time. As shown, the valve assembly 95 is secured to the rod 94 by means of bracket members 92 and 93, which brackets are above and below the cylinder 91. The valve assembly 96, with cylinder 98, is attached to the cylinder 91 by means of the clamp member 97. Such an arrangement lends great flexibility to my pump and greatly enlarges its usefulness.

My pump may be employed in a multitude of technical and exact operations, in both laboratory and industrial work, moving single or plural streams of fluid, and/or simultaneously moving plural streams of unlike fluids, and mixing them in predetermined quantities, if and as desired. It will circulate and/or mix streams of gas and/or liquids in operations of aerating, impregnating, compounding, admixing, diluting, titrating, absorbing, heating, cooling, dissolving, coloring, and chemically uniting, ad infinitum.

To operate the pump, electric motor 66 is energized, causing the gears 6, 7, 8 and 9 to rotate in the directions indicated by arrows thereon. The gears 7 and 9, being fixed to their respective axles 10 and 11, will cause the cranks 14, 15, 16 and 17 to rotate, carrying their respective shafts 28, 29, 30 and 31 with them.

It may be seen that the crank 14 turns in the opposite direction from crank 17; and crank 15 turns in the opposite direction from crank 16.

It should be noted that the outer ends of the cranks describe a circle; and that the outer end of crank 14 is 90 degrees out of phase with the outer end of crank 15; that the outer end of crank 16 is 90 degrees out of phase with the outer end of crank 17; that the outer end of crank 14 is 180 degrees out of phase with the outer end of

crank 17; and that the outer end of crank 15 is 180 degrees out of phase with the outer end of crank 16.

Therefore, when the outer end of crank 14 is at its lowest position, the outer end of crank 17 will be at its highest position. The same applies to cranks 15 and 16. The valve assemblies 52, 53, 54 and 55, being carried by the rods 28, 29, 30 and 31, respectively, will describe arcuate orbits responsive to the movement of the outer ends of the respective cranks which carry them.

In other words, when valve assembly 52 is at its lowest position in its orbicular movement, the valve assembly 55 will be in its highest position in its orbicular movement. The same applies to valve assemblies 53 and 54.

Various indeed may be the mechanical devices and contrivances which employ the essential principles of my invention. The method of this invention may be employed without using the particular mechanism disclosed in the drawings. For instance, other contrivances may be used to tilt the valves, and still further devices may be employed for alternately raising and lowering the separate valves of an associated pair of valves, such as a see-saw contrivance, having valves on the opposite ends of the see-sawing member. Also, there may be employed a rocking structure, roughly comparable to a child's rocking horse, providing valves on the upper ends of the separate rockers, or on the superstructure arranged above such rockers; and an unbalanced eccentric member may be used as a valve-tilting means.

My method may be practiced where there are two associated and related fluid-controlled and gravity-operated valves, each being provided with its own receptacle (moving in unison therewith). Any suitable contrivance which will alternately raise and lower these valves may be employed, and any means which effects a tilting of the valves, first one way and then the other, will do. Then the only other thing needed is a liquid piston moving in a flexible conduit which communicates with each of the receptacles indicated, so as to alternately enter and recede from these receptacles, as they are successively raised and lowered (with respect to one another). That explains my method in a nut-shell.

However, for the sake of clarity, let us now return to an exposition of the particular device made plain in the attached drawings, it being an abundantly operable and one preferred form of mechanism for employing my method.

Since all of the valves, with their associated cylinders, pistons, shafts and cranks, operate the same way, the operation and function of the pump may be more easily and readily understood by describing the action of one of the valves and its associated cylinder and piston, during one complete cycle of operation.

Therefore, for purpose of illustration, we will trace and describe the action of valve assembly 52 and its associated cylinder 42, piston 68, rod 28 and crank 14.

Assuming that the pump shown in Fig. I is in operation, the outer end of crank 14 is moving in a counterclockwise direction, and the cylinder 42 and the valve assembly 52 are moving upward. As the cylinder moves upward, the mercury 79 moves downward in the cylinder, since the mercury seeks to maintain its level in the piston tube 68.

The mercury, moving downward, will draw fluid in through the branch 56 and connecting stem 60 into the cylinder 42. As the valve assembly

52 moves upward, it is tilted to the left and the mercury 62 flows over to the left, and closes the opening through the branch 56a, thus closing the outlet communication between the cylinder 42 and the collecting tube 74.

When the valve assembly 52 reaches the highest part of its arcuate movement, it starts downward and is tilted to the right, causing the mercury 62 to move over to the right and close the opening through the branch 56.

As the valve assembly 52 and the cylinder 42 move downward, the mercury column 70 will move upward, and into the cylinder 42, thus forcing the fluid in the cylinder out through branch 56a (which is now open) and through the collecting tube 74, into the five-way collecting tube 72 and out through the discharge hose 73.

Thus the fluid drawn into the cylinder 42 on the upward movement of the valve assembly 52 is discharged out of the cylinder on the downward movement of the valve assembly 52.

When the outer end of crank 14 reaches the lowest point in its circular rotation, it will begin to move upward again, and the valve assembly 52 will be again tilted to the left, the mercury 62 will again flow over to close the outlet passage through the branch 56a, the mercury 70 will again begin to recede from cylinder 42 and fluid will again be drawn in through the branch 56 and into the cylinder 42. Thus, a complete cycle of operation has been completed.

From the foregoing description it may be generally said that when either of the valve assemblies is moving upward, fluid will be drawn into its associated cylinder; and when the valve is moving downward, fluid is being discharged from the cylinder.

The cylinder 42 and the cylinder 45 are connected together, and they communicate with each other, by means of flexible piston tube 68, which has a column of mercury 70 therein.

Now since the crank 14 is rotating in the opposite direction from crank 17, and the outer ends of said cranks are 180 degrees out of phase, the valve 55 and cylinder 45 are always moving downward when the valve 52 and cylinder 42 are moving upward; and while valve 52 is taking in fluid through branch 56, the valve 55 is discharging fluid through branch 59a into collecting tube 77, through the five-way collector tube 75 and out through the discharge tube 73.

At the position in which we see valves 52 and 55 in Fig. I, the valve 55 is on its downward movement and is therefore discharging through the branch 59a; and the valve 52 is on its upward movement, and fluid is being drawn in through the branch 56. The mercury column 70 is moving downward in the cylinder 42 and upward through the tube 68 and into the cylinder 45, thus forcing the fluid which has collected in cylinder 45, while valve 55 was in its upward movement, out through the branch 59a.

The valves 53, 54 and 55 are exactly the same in construction and operation as has been related above in reference to valve 52, which is of suitable and typical construction.

The cylinders 43 and 44, which operate in conjunction with the valves 53 and 54, respectively, are connected together by the flexible piston hose 69, in the same manner that valves 52 and 55 are connected together; and they function together in the same manner as was related above in reference to valves 52 and 55 (which latter valves are typical).

It should be noted that the outer ends of the

cranks 15 and 16 are also 180 degrees out of phase, and that they are rotating in opposite directions; so that when valve 53 is moving upward, and fluid is being drawn in through the branch 57 and into the cylinder 43, the valve 54 is moving downward, and fluid is being discharged through branch 58, in the same manner that was related above in reference to valves 52 and 55.

Now since the outer ends of cranks 14 and 15 are 90 degrees out of phase in their circular movement, and the outer ends of cranks 16 and 17 are 90 degrees out of phase with each other in their circular movement, it may be seen that there is a discharge of a cylinder full of fluid by each of the four valves through the discharge hose 73 during each cycle of operation of the pump. Since the valves discharge 90 degrees apart, then four cylinders full of fluid will be discharged by the pump at 90 degree spaced intervals during one complete cycle of operation of the pump. Thus, by regulating the speed of the pump a continuous flow of fluid may be obtained.

For the purpose of illustrating the direction of in-flow and out-flow of fluid through the valves, the valves 52 and 55 are shown in Fig. V separate and apart from the rest of the pump. In this illustration the relative positions of the valves 52 and 55 are shown while one is discharging fluid and the other is taking in fluid. Valve 52 as shown in solid lines in this illustration is on its way up and fluid is being taken in through branch 56 and through connecting stem 60 (as indicated by arrows); and the valve 55 as shown by solid lines is on its way down and fluid is being discharged through branch 59a out of the cylinder 45 (as is shown by arrows). The valve 52 as shown by dotted lines is on its way down in its arcuate movement, and fluid is being discharged through branch 56a (as shown by arrows); and valve 55 as shown by dotted lines is at the same time on its way up and fluid is being taken in through branch 59 (as shown by arrows).

The arcuate movement of two cooperating valves such as 52 and 55, shown in Fig. I, and the relative positions thereof during one complete cycle of the pump, is shown diagrammatically in Fig. IX.

In this illustration the valves 99 and 100 are carried by the rods 102 and 103, respectively. The rods 102 and 103 are rotatively carried by the outer ends of the crank arms 104 and 105, respectively. The cranks 104 and 105 are secured to, and rotate with, the axles 104a and 105a, respectively. The valves 99 and 100 are connected by a flexible piston tube 101. The valve 99 has a quantity of mercury 106 therein; and valve 100 has a quantity of mercury 107 therein.

When set in motion, the outer end of crank 104 describes the circle 108, in the direction indicated by arrows; and the outer end of crank 105 describes the circle 109, in the direction indicated by arrows. It is to be noted that the two cranks are revolving in the opposite directions. The valve 99, being carried on the upper end of rod 102, will describe the figure 110, in the direction indicated by arrows; and the valve 100, being carried on the upper end of rod 103, will describe the figure 111, in the direction indicated by arrows, it being observed that the two valves move in opposite directions.

Assuming that the rotation begins when the cranks 104 and 105 are in the positions indicated by Arabic numeral 1 and Roman numeral I, respectively, then the valve 99 is moving upward and is taking in fluid at the place and direction

indicated by the arrow; and the valve 100 is moving downward, and it is discharging fluid in the direction indicated by the arrow. When the crank 104 has reached the position 2, the crank 105 has reached the position II; and the valve 99 has passed the highest point of its movement and has started downward; and the valve 100 has reached the lowest point of its movement and has started upward; and fluid is being taken in to valve 100 and discharged by the valve 99, as indicated by arrows on the respective valves.

When arm 104 has reached position 3, the valve 99 is still on its way down; and crank 105 has reached the position III, and the valve 100 is on its way up; and fluid is being taken into the valve 100, and discharged from the valve 99, in the directions indicated by arrows. When the crank 104 has reached the position 4, the valve 99 has been tilted to the left and has started up, and is taking in fluid in the direction indicated by the arrow; and arm 105 is in position IV, and valve 100 is on its way down, and is discharging fluid in the direction indicated by the arrow.

Thus, it will be observed that the valves 99 and 100 are always 180 degrees out of phase in their arcuate movement; and that while one is taking in fluid, the other is discharging it.

The foregoing diagrammatic illustration and description applies either to the cooperating valves 52 and 55 or to cooperating valves 53 and 54. It should be remembered, however, that the outer ends of arms 14 and 15 are 90 degrees out of phase in their arcuate movements; and that the outer ends of arms 16 and 17 are 90 degrees out of phase in their arcuate movements, so that each of the valves 52, 53, 54 and 55 completely discharge alternately, at 90 degree intervals, on each complete cycle of the pump; and thus we have a continuous flow.

Should an intermittent discharge be desired, any one or more of the valves could be disconnected from the five-way discharge tube 72, so that only the valves left connected would discharge through the discharge tube 73. The disconnected tube leading from the valve would be closed by a clamp or otherwise, to prevent outside communication with the enclosed system. Any one of the valves will discharge independently of the other valves.

Should it be desired to cause the pump to operate as a suction pump, this may be accomplished by merely reversing the rotation of the motor 66, by a reversing switch (not shown), so that fluid will be drawn in through the discharge tube 73 and discharge through the free ends of the branches 56, 57, 58a and 59. A steady suction may be maintained by using all four valves, or an intermittent suction may be created by merely disconnecting one or more of the valves from the collecting tube 72, in the manner described above.

The amount of fluid pumped depends upon the volume of the cylinder or reservoir underneath the valve assembly, which cylinder or reservoir is indicated as at 42 in Figs. II and III. By increasing the volume of this reservoir the volume of the pump may be increased; and by decreasing the volume of this cylinder the volume of the pump is decreased.

The pump may be made to accurately pump very small quantities of fluid by making the valve 70 substantially in accordance with the modification shown in Fig. IV.

In this modified valve, the valve assembly is indicated as 18, which may be constructed as a unitary tube with upstanding branches 80 and

81, and inverted U-shaped connector stem 82 which is extended to form the downwardly projecting tube 79. The tube 79 serves as the cylinder or reservoir in which fluid is stored and from which it is discharged. Since the interior volume of the modified tube 79 is very small, the amount of fluid which is discharged by this valve is very small. In a preferred form of this modification, the internal diameters of members 17, 79, 80, 81 and 82 are made to be the same.

Connected to the cylinder 79 is the connector tube 85, which may be extended to connect to a duplicate of valve assembly 18 on the opposite side of the pump. The valve assembly 18 may be secured to the rod 84, which carries it by means of the clamp member 83.

Since mercury is a contaminant for many liquids, it may be desired to use the assembly shown in Fig. VII in conjunction with my pump, when pumping liquid. This special assembly consists of a container 86, in which there is a stopper 87, with two holes therethrough. Through one of these holes passes a tube 89, which is bent to form a siphon. Since both ends of the tube are exactly the same length, no fluid will be siphoned. Through the other hole of the stopper is passed a tube which extends into the fluid 90 in the bottle to exactly the same depth as the immersed end of the siphon tube 89, thus equalizing the hydrostatic pressure in the container. The discharge tube 73 of the pump is connected to the outer end of the tube 88. Air is pumped by the pump into the container 86 through the tube 88. The volume of air pumped into the container will displace a proportional volume of liquid in the container and will force the liquid out through the siphon tube 89. Thus, we have a liquid pump in which the mercury piston and in which the mercury employed as valving means never comes into contact with the liquid being pumped.

The pump may be modified to pump different fluids and/or different quantities of the same fluid at one and the same stroke by using the modification shown in Fig. VIII. This modification, which has been described heretofore, has a valve assembly like that shown in Figs. II and III mounted in conjunction with a valve assembly like that shown in Fig. IV; and both are mounted on the same rod 94. With this arrangement one quantity of fluid could be pumped by the valve assembly 96. Of course each of the separate valve assemblies would be connected to its own collector tube like that shown at 72. This arrangement can be multiplied, and thus would be particularly useful when it is desired to mix several different kinds and quantities of fluids at the same time, and in predetermined quantities or in related volumes. By using the adaptation shown in Fig. VII, a gas and a liquid could be mixed or several gases and liquids could be mixed at the same time.

The pump could be further modified to serve the function of a circulating pump. To do this it would only be necessary to connect the free branches 56, 57, 58a and 59 on the valves 52, 53, 54 and 55 to an assembly exactly like that made up of connector tubes 74, 75, 76 and 77, five-way collector tube 72 and discharge tube 73. The discharge tubes of the two assemblies could be each connected to the receptacle or container through which it is desired to circulate fluid; and we would in effect have a circulating pump.

In order to measure the exact amounts of fluid pumped, a counter 112 may be mounted on the

11

base member 1. This counter has a trip arm 113 which is tripped by the crank arm 15 on each revolution thereof, so that, by calibration, the exact amount of fluid pumped can be determined by the number of revolutions indicated on the counter. The fluid can thus be pumped in counted and metered quantities.

The amount of fluid pumped can of course be varied by varying the speed of operation of the pump, up to its maximum efficiency.

This pump is particularly useful in laboratories and in scientific work, where it is required to pump varied quantities of fluids, and particularly in minute amounts, without change in the pressure, volume or temperature of the fluids; or where it is desired to pump spaced and metered quantities of fluid in which each quantity moved by the pump will remain constant in volume, pressure and temperature while travelling through the pump. It may, of course, have commercial application wherever such results are desired.

For instance, it may be particularly useful in pumping highly volatile explosive or inflammable fluids, such as gasoline or nitro-glycerin. The fluid piston and valves cause no friction or pressure and there is, therefore, no heat (created by operation of the pump) which can come into contact with fluid being pumped. Thus the danger of fire or explosion when pumping explosive or inflammable fluids is greatly minimized.

My pump may be employed in the preparation of pharmaceuticals, medicaments, anesthetics and solutions and mixtures which are required to be germ free, chemically pure and sterile. The closed system of moving fluids which I employ prevents contamination or bacterial presence from the air. My no-pressure system of pumping allows the movement and/or mixture of fluids without altering their physical properties in any way, or in the least affecting their normal temperature, or volume.

For instance, using the auxiliary liquid chamber, blood or blood plasma may be moved without any damage whatsoever thereto. Fluids may be introduced into the body of a patient continuously, and in minute and exactly measured quantities, without the necessity of personal measurement or supervision. The pumping device may be set to deliver the required quantity of any fluid, over a certain time, as, for instance, a penicillin solution into the vein of a patient, where it is desired that it be deposited in a certain concentration and at a certain spot, intermittently or continuously, for many hours, or even days, without ceasing. Or, it could be used to continuously evacuate the stomach of a patient by converting it into a vacuum pump, in the manner hereinbefore described. The valve arrangement would prevent any undue suction that might injure the stomach of the patient, and the suction may be regulated by decreasing or increasing the volume of mercury in the valve.

Aeration of water or other liquids may be effected by having pumped therein washed and cleansed air, or oxygen, continuously and in given proportions, without surcease. Even air may be purified and made sterile, or freed of pollens, dusts and allergy producing materials through the use of my invention.

Saline solutions may be made in a given strength continuously, by the dilution of a concentrate thereof; and such a solution may be fed continuously (or intermittently) to open wounds, as a cleansing antiseptic. The tech-

12

nical, scientific and laboratory uses of my invention are numberless; and its industrial uses are many.

Although I have illustrated and described the preferred forms of my invention, it is to be understood that other and further changes and modifications may be made therein without departing from the spirit and scope of the appended claims.

10 I claim:

15 1. In a pump of the class described, a pair of gravity biased liquid operated valves, each of said valves having an inlet and an outlet and a common conduit connecting the inlet and outlet; a cylinder extending below each of the valves; a tube connecting the upper portion of each cylinder with the upper side of the common conduit of the valve associated with such cylinder; a flexible conduit providing communication between the two cylinders; a liquid piston arranged within said flexible conduit; means for rotating said cylinders out of phase and in a substantially common plane and for tilting the valves back and forth.

25 2. In a pump of the class described, a pair of gravity biased liquid operated valves; an inlet for each said valve; an outlet for each said valve and a common conduit connecting the inlet and outlet of each valve; a cylinder extending below each of the valves; a tube connecting the upper portion of each cylinder with the upper side of the common conduit of the valve associated with such cylinder; a flexible conduit providing communication between the cylinders; a liquid piston movable within said flexible conduit; means for rotating said cylinders out of phase and in a substantially vertical common plane, and to impart tilting motion to said valves; a collecting vessel; a common outlet for said collecting vessel; a separate tube connected to the outlet of each said valve, said tubes being connected at their remaining ends to the collecting vessel, whereby fluid pumped through each valve may be discharged through the common outlet.

30 3. In a pump of the class described, a pair of gravity biased liquid operated valves, each of said valves having an inlet and an outlet and a common conduit connecting the inlet and outlet; a cylinder extending below each of the valves; a tube connecting the upper portion of each cylinder with the upper side of the common conduit of the valve associated with such cylinder; a flexible conduit connecting the cylinders; a liquid piston movable within said flexible conduit; means for rotating said cylinders in a substantially vertical plane, each of said cylinders being 180 degrees out of phase with the other in its arcuate movement, said rotating means also operating to tilt each of said valves, said tilting being so arranged and operated as to reverse the angle of tilt at the highest point and again at the lowest point of the arcuate movement of each of said cylinders.

35 4. In a combined valve and cylinder for use in a pump of the class described, a pair of upstanding branches; a substantially horizontally disposed conduit connecting said branches; a body of liquid disposed in said conduit in sufficient quantity to close either of said upstanding branches when the valve is tilted in the direction of the branch to be so closed; a cylinder extending below the conduit; and a tube extending above the conduit and connecting the upper part of the conduit and the upper part of the cylinder, the said cylinder, upstanding branches,

conduit and connecting tube being carried by common supports whereby they may be moved in unison.

5. In a pump, a pair of cylinders; a flexible conduit connecting such cylinders; a liquid piston so disposed in said conduit as to be movable therein by force of gravity toward whichever end thereof is lower; a separate liquid operated valve arranged to communicate with each cylinder, each such valve having a substantially horizontally disposed conduit with an upstanding branch at each end thereof, and sufficient liquid in the conduit to alternately flow by gravity to open and close the branches when the valve is alternately tilted in opposite directions; a tube connecting the upper part of the cylinder and the upper side of the conduit; whereby fluid is admitted to its associated cylinder when the said valve is tilted in one direction and the cylinder is raised, and fluid is discharged from the cylinder when the valve is tilted in the other direction and the cylinder is lowered; means for raising and lowering said cylinders alternately, and for alternately tilting each valve in different degrees of inclination.

6. In a pump of the class described, two pairs of gravity biased liquid operated valves; an inlet for each valve; an outlet for each valve; a common conduit connecting the inlet and outlet; a separate cylinder connected to and communicating with both inlet and outlet on each of said valves; said cylinder extending below the valve; a tube extending above the valve and connecting the upper end of the cylinder with the upper side of the common conduit of the valve; a flexible conduit connecting the cylinders on each pair of valves and causing communication therebetween; a separate liquid piston movable within each of said flexible conduits; means for so rotating each pair of valves and associated cylinders as to cause them to move out of phase and in a common plane, and for effecting reversible inclination in each of said valves.

7. In a pump of the class described, two pairs of gravity biased liquid operated valves; an inlet for each such valve; an outlet for each such valve; a common conduit connecting the inlet and outlet; a separate cylinder communicating with the inlet and outlet on each valve; a tube extending above the valve and connecting the upper end of the cylinder with the upper side of the common conduit of the valve; a separate flexible conduit connecting the cylinders of each pair of valves; a separate fluid piston movable within each of said flexible conduits; means for rotating each cylinder in a substantially vertical plane, each cylinder of each pair of cylinders being 180 degrees out of phase with the other cylinder thereof in their arcuate movement, and each cylinder in each pair of cylinders being 90 degrees out of phase with one cylinder in the other pair of cylinders and 180 degrees out of phase with the other cylinder in said other pair of cylinders in their arcuate movement, said rotating means operating to tilt each of said valves, such tilting being so arranged and oper-

ated as to reverse the angle of tilt at the lowest point and again at the highest point in the arcuate movement of the cylinder communicating with such valve.

- 5 8. In a pump of the class described, two pairs of gravity biased liquid operated valves; an intake branch on each valve; an outlet branch on each valve; a horizontal conduit connecting the branches; a separate cylinder extending below and communicating with each such pair of branches; a connecting tube connected to the upper end of the cylinder and to the upper side of the conduit; separate flexible conduits connecting the cylinders of each pair of valves; a separate liquid piston movable within each flexible conduit; means for rotating each pair of valves, together with their associated cylinders, in vertical planes, each valve in each pair of valves being 180 degrees out of phase with the other valve in such pair in their arcuate movement, and the valve in one pair being 180 degrees out of phase with the diagonally disposed valve in the other pair in their arcuate movement, said rotating means also operating to impart a tilting motion to each of said valves at the lowest point and also at the highest point in the arcuate movement of each of said valves with associated cylinder; and a common collecting conduit so connected to one branch of each of said valves as to receive fluid discharged therefrom.

- 20 9. In a pump of the class described, two pairs of gravity biased liquid operated valves, an inlet for each valve; an outlet for each valve; a common channel connecting inlet and outlet; a separate cylinder extending below and being attached to each such valve and arranged to communicate with both inlet and outlet thereof through the common channel; a tube extending above the valve and being connected to the top of said cylinder and to upper side of the common channel; a flexible conduit connecting the cylinders of each pair of valves and providing communication therebetween; a liquid piston movable within each such flexible conduit; means for vertically rotating said cylinders together with their associated valves out of phase, said means also operating to impart tilting motion to each valve at the lowest point and again at the highest point in the arcuate movement of its associated cylinder; a collecting tube; a separate tube connected to the outlet of each valve, the said tubes being connected at their remaining ends to the collecting tube, whereby the fluid moved through the pump is delivered into the common discharge conduit; and a counter adapted to be actuated on each cycle of the pump whereby the volume of fluid being delivered may be measured.

LOUIS W. LEWIS.
